UNITED STATES PATENT OFFICE.

LEONARD CHARLES SMITH, OF CHICORA, MISSISSIPPI.

SAW GUIDE.

Application filed January 16, 1928. Serial No. 247,158.

The present invention relates to improvements in saw guides, and has for an object to provide an improved guide for band saws in which the guide is adjustable, productive of less friction, and of longer life than the guides now in use.

Other objects of the invention are to provide a guide of extremely simple construction which admits of easy adjustment and which is capable of installment in present forms of band mills without involving any alteration in standard constructions.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a fragmentary plan view of a guide supporting arm and saw illustrating the improved guides.

Figure 2 is an enlarged central vertical section through one of the guide pins with the core in elevation.

Figure 3 is a central vertical section of both the core and housing and shows the core in a slightly different position from that in Figure 2, and

Figure 4 is a cross section along the line 4-4 of Figure 2 and looking in the direction of the arrows.

Referring more particularly to the drawings 5 designates generally the arm to be found in a standard band mill, having the slot 6 through which passes the band saw 7.

This arm supports the guide blocks or guide pins, in a well known manner. At one side are provided fixed guide pins 8 in any appropriate number, while at the opposite side of the band saw 7 are provided a number of adjustable pins. The present invention is concerned with the construction of the adjustable pin.

This improved adjustable pin comprises generally a housing 9 of metal or other appropriate material, and a core 10, preferably of wood.

One end of the housing 9, which is preferably cylindrical is left open, while the other end 11 is closed and receives rotatably therethrough a threaded adjusting screw 12 having the head thereof on the exterior for the purpose of rotation and angular adjustment.

A lock nut 13 on the shank of the screw 12

and spaced from the head thereof is arranged to engage the inner face of the end wall 11, whereby to restrain the screw from axial movement but to permit of the rotation thereof.

A guide pin or lug 14 projects inwardly from the cylindrical side wall of the housing 9 and is adapted to take into a longitudinal groove 15 made in the cylindrical external portion of the wooden core 10.

The wooden core, at its inner end, is adapted to strike the lock nut 13 and also a shoulder 16 made upon the interior of the housing or shell 9. The shell or housing 9 is provided with the external screw threads 17, whereby the entire guide device, as a unit, may be screwed into the usual threaded opening found in the guide arm 5.

The core, besides having the longitudinal slot 15 therein, to cooperate with the pin or lug 14, is further modified by having produced therein an axial recess 18 which opens through the inner end of the core and traverses a substantial portion of the length thereof terminating, as indicated at 19, whereby to leave a substantial solid and uninterrupted thickness at the outer portion of the core 10. The axial recess 18 is intersected by a transverse through opening 20 in the core body. This transverse opening is made intermediate the ends of the core and preferably, though not necessarily, nearer the inner end. In this opening 20 is inserted a brass or other plug 21, which may also be of generally cylindrical form and having a threaded passage 22 therethrough registering with the axial recess in the core. The threads of the passage 22 are in lead with those of the screw 12 and the axial recess 18 may also be tapped with a like thread. The ends of the metallic plug 21 may be flush with diametrically opposite peripheral portions of the core body 10 and may be rounded to conform to the external cylindrical curvature of the plug 10; or the length of the plug 21 may be slightly in excess of the external diameter of the core 10 to permit the rounded end portions of the plug to engage the interior cylindrical wall of the cylindrical shell 100

or housing 9; while leaving a slight clearance between the shell and the core 10.

In the use of the device, the improved guide pins are mounted in the arm 5 by securing the housing or shell threads 17 in the threaded openings of the arm 5. The fixed blocks 8 engage the saw 7 at one side, and

the adjustable cores 10 engage the saw at the opposite side. These guide pins may be provided in any suitable number, three being shown for purposes of illustration only. 5 The improved pins replace those on the back side of the guide. The cores 10 are prevented from rotation due to the slot 15 and pin 14 construction. However, the wooden cores 10 may be adjusted toward and from 10 the saw by rotating the screws 12 which give a minute adjustment. During the adjusting movement of the cores 10, wear will be taken up by the plug 21 and will not be allowed to devolve upon the wooden parts. 15 The improved pin is to be used as a replacement of the guide pin now generally furnished by manufacturers which is usually made of Babbitt or composition metal. This 20 wooden pin or core will not heat under friction as readily as metal, and much greater strain or pressure may be brought to bear against the blade of the saw. The life of the improved pin is much longer than those made of metal, and in use does not have a tendency 25 to cause the saw to harden and crack, as does the metal pin. These improved pins may be used on both upright and horizontal band mills. In the manufacture of the cores, lignum vitae wood is preferable, though dog- 30 wood, persimmon or other native hardwoods may be used.

To properly use the improved pins in an upright mill, the upper wheel is set back one-quarter inch from perpendicular. This takes 35 care of the over-throw of the saw, stiffening and steadyng it. In a horizontal mill, the method of use is the same, except that the pins are used in the guide operating on the saw at the driving wheel of the mill.

It is obvious that various changes and 40 modifications may be made in the details of construction and design of the above specifically described embodiment of this invention without departing from the spirit thereof, such changes and modifications 45 being restricted only by the scope of the following claims.

What is claimed is:

1. A saw guide comprising a carrying shell, a movably mounted core therein, a wear 50 plug in the core, and adjusting means carried by the shell for engaging the plug.

2. In a saw mill a saw guide comprising a shell having means for mounting it in a supporting part of the mill, an axially movable core in the shell, a wear plug embedded in the core for engaging the shell, means between the shell and plug for restraining the latter from rotation, and an adjusting screw carried by the core for threaded engagement 60 with the plug.

3. A saw guide comprising a metallic threaded shell open at one end and closed at the opposite end, a rotary adjusting screw carried in the closed end of the shell, means for restraining the adjusting screw from axial travel, a pin projecting within the shell, a wooden core having a slot to receive said pin and an axial recess to receive the adjusting screw, said core also having a transverse 70 passage intersecting the recess, and a metallic wear plug fitted in said transverse passage having rounded ends to engage the shell and a threaded passage in registry with the recess for engaging the threads of the adjusting 75 screw.

LEONARD CHARLES SMITH.
